(57) **CLAIM**

The ornamental design for a combination purse and seat cushion, as shown and described.

DESCRIPTION

FIG. 1 is perspective view of a first embodiment of the combination purse and seat cushion in accordance with the design in its closed position;

FIG. 2 is a top view thereof;

FIG. 3 is side view thereof;

FIG. 4 is an end view thereof;

FIG. 5 is a bottom view thereof;

FIG. 6 is a bottom view thereof in its open position;

FIG. 7 is an end view thereof in the open position;

FIG. 8 is a top view thereof in the open position; and,

FIG. 9 is a side view thereof in the open position.

The broken lines showing stitching and a zipper are for illustrative purposes only and form no part of the claimed design.
